SKI POLE HANDLE

Emery J. Woodall, Jr., Brooklyn, N.Y., assignor to Bar-
reca Products Co., Inc., Brooklyn, N.Y., a corporation
of New York

Filed June 6, 1961, Ser. No. 65,484

Term of patent 14 years

(Cl. D34—5)

FIG. 1 is a front elevational view of a ski pole handle showing my new design;

FIGURE 2 is an elevational view of one side thereof;

FIGURE 3 is a rear elevational view thereof;

FIGURE 4 is an elevational view of the other side thereof;

FIGURE 5 is a top plan view thereof; and

FIGURE 6 is a bottom plan view thereof.

I claim:

The ornamental design for a ski pole handle, substan-
tially as shown.
